(57) **CLAIM**

The ornamental design for a harvested game trophy tag, as shown and described.

DESCRIPTION

FIG. 1 is a perspective view of the harvested game trophy tag installed on an antler of a harvested game as intended; FIG. 2 is a top view of the harvested game trophy tag in an uninstalled condition;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines depicting antlers in FIG. 1 are for the purpose of illustrating environmental matter that form no part of the claimed design, and the remaining broken lines in all drawings depict portions of the harvested game trophy tag that form no part of the claimed design.

1 Claim, 5 Drawing Sheets
